SOUND RECORDING APPARATUS

Edward W. Kellogg, Moorestown, N. J., assignor to
Radio Corporation of America, a corporation
of Delaware

Application October 17, 1940, Serial No. 361,560

10 Claims. (Cl. 179—100.3)

This invention relates to improved ground noise reduction apparatus and, more particularly, to an amplifier circuit which is adapted to respond to electrical impulses corresponding to sound impulses in such a manner as to provide the most desirable ground noise reduction characteristics in recording. This amplifier provides a sufficiently rapid response to the sound impulses without either providing so much clearance as to produce undue ground noise or clipping the peaks of the sound wave records.

Although the apparatus hereinafter described is described with particular reference to its application to a variable area sound recording apparatus, it will be understood that it is equally applicable to variable density recording apparatus and that the description in conjunction with variable area apparatus is given for the reason that it is easier to visualize the operation of the various parts and the types of records produced.

When any sound wave is produced, it consists of a series of compressions and rarefactions of the air. In the compressions, the pressure and the air density are, of course, greater than the normal atmospheric pressure, and the reverse is true of the rarefactions. Accordingly, I herein-after refer to the compressive peaks of the sound waves as positive peaks and to the peaks of rarefaction as negative peaks.

As was pointed out in my paper entitled "Starting characteristics of speech sounds," published in the Journal of the Society of Motion Picture Engineers, volume XXXIV, page 43, there are often positive peaks of appreciable magnitude considerably in advance of the negative peaks of the same sounds, and the positive peaks in a continued sound frequently exceed the negative peaks in amplitude, while the reverse is rarely the case.

Due to the characteristics of sounds, it is customary in the art to connect the recording galvanometer light valve or other light-controlling device to the amplifier in such a manner that the direction of greatest permissible swing is in the same direction as the positive peaks of the sound waves. When ground noise reduction apparatus is used with such sound-recording apparatus, due to the characteristics of the light-controlling device the polarity is such that the positive peaks are directed away from the ground noise reduction control and the ground noise reduction apparatus follows the general contour of the negative peaks. As a result of this, the movement of the ground noise reduction apparatus is kept to a minimum.

This prior art arrangement had a number of disadvantages which are overcome by the present apparatus. In the sound waves which have a plurality of positive peaks before any appreciable negative peak amplitude is reached, there would be no appreciable movement of the shutter during the period of negligibly small negative peaks and, when the negative peaks would appear, they might be of considerable amplitude, thereby causing clipping of a number of waves. This could be avoided by using full wave rectification, but the use of full wave rectification is undesirable for the reason that the amplitude of the positive peaks is in many instances so much higher than that of the negative peaks of the average that too much margin would be produced on the negative side of the record. It is desirable, however, to use a portion of the amplitude of the positive peaks to cause initial opening of the ground noise reduction apparatus, but to limit the effective amplitude so that it cannot greatly exceed the average amplitude of the negative peaks. During a crescendo, each successive peak is, of course, higher than the preceding one, and, in this case, if a portion of the energy of the positive peaks can be added to that of the negative peaks, it will considerably assist in preventing clipping.

Since the usual ground noise reduction circuit is of the peak-responsive type which opens in response to the peaks and proportionally to the height of the peaks and thereafter gradually closes, the addition of a portion of the positive peaks equal in height to the negative peaks will assist in preventing clipping merely due to the shorter interval between peaks. The positive peaks will assist still more in preventing clipping during crescendos, even though they be limited in amplitude, because in so many instances the positive peaks come first. If the positive peaks as applied to the ground noise reduction system are limited to a value less than that of the negative peaks, as, for example, when the latter are of moderately high amplitude, the positive peaks may still advantageously be included in such a manner that they provide a limited margin of response of the ground noise reduction system above that produced by the negative peaks alone. Such margin will take care of a moderate unexpected increase in the height of the negative peaks. Therefore, in order to obtain the benefits just described, in accordance with my present invention, I employ a circuit which limits the magnitude of the positive peaks applied to the ground noise reduction system,

and cause these peaks to contribute a limited amount to the total response of the ground noise reduction system.

One object of my invention is to provide an improved ground noise reduction circuit.

Another object of my invention is to provide an improved type of rectifying amplifier.

Another object of the invention is to provide an improved form of peak-reading circuit.

Another object of the invention is to provide a ground noise reduction apparatus for use in sound recording which will respond with reasonable accuracy to the envelope of the waves.

Another object of the invention is to provide a ground noise reduction circuit in which the impulses due to the negative wave peaks are combined with a certain portion of the impulses due to the positive wave peaks.

Another object of the invention is to provide a ground noise reduction circuit in which impulses due to the positive wave peaks are combined with impulses from the negative wave peaks up to but not materially exceeding the amplitude of the negative wave peaks.

Other and incidental objects of the invention will be apparent to those skilled in the art from a reading of the following specification and an inspection of the accompanying drawings, in which—

Figure 1 shows one form of the invention in which the positive wave peaks are limited to a predetermined amplitude, and contribute a limited amount to the total control voltage which determines the response of the system.

Figure 2 shows a second form of the invention in which the wave peaks of both polarities, in a portion of the circuit, are limited to a predetermined amplitude and applied to the circuit in a different manner from that shown in Figure 1, for providing a margin of response above that produced by the unlimited negative peaks.

Figure 3 shows a modification of the invention in which the limiting voltage applied to the positive wave peaks can be raised during crescendos.

Figure 4 shows a modification of the form of the invention shown in Figure 3 in which a photocell is used for controlling the rate of discharge or recovery of the system, and

Figure 5 shows a form of the invention in which the voltage applied by the positive peaks is controlled by the voltage built up by the negative peaks.

In Fig. 1, the audio input to the ground noise reduction system is applied to the primary winding of transformer 10. This transformer is provided with two secondary windings 11 and 12 each of which operates rectifiers 14 and 23, respectively. The outputs of the rectifiers are independently filtered, that from rectifier 14 being filtered by condensers 16 and 18 in cooperation with resistance 17, and the output from the rectifier 23 is filtered by condensers 25 and 27 in cooperation with resistance 26. The final output after filtering consists in the voltage across condensers 27 and 18 in series and is thus strictly additive. After modulation ceases, condenser 16 discharges through resistance 15 while condenser 25 discharges through resistance 24, thus providing for recovery of the circuit to normal zero modulation condition. The summation voltage is applied between cathode and grid of output tube 19 whose cathode-to-anode current passes through the winding of shutter 28.

The upper circuit as shown in the figure comprising rectifier 14 and its associated filtering elements functions as in present ground noise reduction systems to provide an envelope voltage across the condenser 18 which is derived entirely from the negative peaks of the input audio voltage. Thus, if condenser 27 were short-circuited, the system would operate exactly as in present ground noise reduction systems. The overall response of the system can be so adjusted that the displacements of the shutter are just sufficient to clear the tops of the waves in the recording system, but it is practically necessary to provide an excess of gain by means of a volume control in the audio frequency system which supplies the input to transformer 10. This margin of excess gain is normally approximately proportional to the magnitude of the modulation and is thus comparatively small in absolute magnitude when the modulation is low, while at higher amplitudes it becomes unnecessarily large. In order to provide a more nearly constant margin, it has been proposed to so load the rectifier or the output of the audio transformer which is applied to the rectifier in a system otherwise identical with the upper circuit of Fig. 1 that, for low modulations, the system has a relatively high gain, and, at higher modulations, the gain is reduced. In a patent application of Glenn L. Dimmick, U. S. Serial No. 358,813, filed September 28, 1940, entitled, "Film sound recorders," and assigned to Radio Corporation of America, this is accomplished by means of a rectifier element and biasing battery similar to the one shown in Fig. 1 and my other figures, and presently to be described. The result produced by the circuit employed in the Dimmick invention is the production of a more nearly fixed margin of shutter opening above that which is required for bare clearance of the peaks of the wave, and this is distinctly favorable to a satisfactory recording from the standpoint of freedom from clipping of wave peaks and avoidance of unnecessarily large margins. The difference between the Dimmick circuit and that of my present invention is that, in my Fig. 1, the rectifier 14 operating on the negative peaks is adjusted for bare clearance and the margin is derived from the positive peaks which operate through rectifier 21. The advantage of employing the positive peaks to produce the margin has already been described. In order that the margin may be achieved for very low amplitudes, the winding 12 of transformer 10 is preferably provided with more turns than winding 11 so that low voltages applied to the primary will produce relatively high output voltages to apply across the rectifier 23. Were no limiting device applied to the margin-producing circuit of Fig. 1, it would cause undesirable large response on the part of the shutter, partly because the positive peaks are likely to be higher than the negative peaks in the original sound waves and partly because of the greater number of turns on winding 12. I therefore employ the limiting device comprising rectifier 21 and biasing battery 22. Whenever a positive peak occurs, it tends to send current through rectifier 23. It will also send current through rectifier 21, provided that voltage produced exceeds that of the bias battery 22. If the peak voltage is less than the voltage of the bias battery, no current will flow through rectifier 21. Rectifier 21 is of such low resistance that it constitutes a heavy load on the audio circuit which comprises the secondary winding 12

of transformer 10. In order that the loading may be more effective in limiting the voltage applied to rectifier 23, the resistance of the circuit is further increased by including a resistor 31, the resistor 31 also serving the purpose of preventing the loading from reacting as much on the voltage produced in winding 11, although this is not an essential feature since the loading affects only the positive peaks and not the negative.

The purpose of resistors 13 and 20 is to cause the audio circuits to have a low effective output resistance particularly to minimize the effect of leakage reactance in the transformer and which might otherwise prevent a sudden flow of current through the rectifiers when this is needed. Since the peaks applied to rectifier 23 are limited to a voltage substantially equal to that of bias battery 22, the entire lower or marginal circuit can produce only a certain limited voltage. This tends to give the desired constant margin.

While there is more to be gained by producing the margin by means of the positive peaks than of the negative peaks, there is no reason why both should not contribute to the margin. There is, in fact, the possibility that the early peaks in the negative direction may exceed those in the positive direction, although this is an exception to the predominating condition. Therefore, in Fig. 2, I have shown a full wave rectifier in the marginal circuit, comprising transformer winding 30 and rectifier elements 23. The output of the full wave rectifier is limited to the voltage of bias battery 22 which is in series with rectifier element 21. The limiting device comprising battery 22 and rectifier 21 is applied in a slightly different manner in Fig. 2 than in Fig. 1. In Fig. 2, it is applied to the rectified voltage, whereas in Fig. 1 the limit was imposed on the voltage before it was applied to the rectifier element. This difference is not essential to the performance of the system and is optional with the designer of the circuit. In the case where a full wave rectifier is used, simplification is served by loading the rectified voltage rather than the audio voltage. The resistor 31 serves the same purpose as in Fig. 1, but is more important in that the negative peaks are loaded by the limiter in Fig. 2 and would, therefore, were it not for the protective effect of resistance 31, also cause a reduction in the height of the negative peaks developed in transformer winding 11.

In U. S. Patent No. 2,222,172 of Nov. 19, 1940, Glenn L. Dimmick has disclosed means for providing a control voltage in a ground noise reduction system which voltage is proportional to the rate of change of grid voltage applied to an output tube, or, in other words, equal to the rate of change of the shutter current. This voltage is high during rapid crescendos and at other times is much less. Figure 3 shows a circuit adapted to make use of such a voltage for increasing the margin of shutter opening during periods of rising amplitude. Figure 3 differs from Figure 2 only in the inclusion of the secondary winding of transformer 32 in series with the biasing battery 22. The limiting voltage supplied by the marginal circuit in Fig. 3 will therefore be dependent not solely on the bias battery 22 but on the sum of battery voltage and the voltage induced in the secondary of transformer 32. The number of turns on the secondary winding is adjusted to give the desired degree of increase in margins during crescendos. During periods of diminishing audio voltage, the voltage provided by transformer 32 is in the reverse direction and

would tend to reduce the margins. This will never do any harm, since small margins during diminishing audio voltage are desirable. In any case, the reduction of margin during diminuendo would be less than the increase during crescendo for the reason that the filter circuits are so designed that the recovery of the circuit when modulation is decreasing is always smaller than the opening during the equally rapid crescendo.

In Dimmick Patent No. 2,222,172 of Nov. 19, 1940, it has been further proposed to control the recovery of the circuit or restoration to zero modulation condition by discharging the condenser 16 through a photocell instead of a simple resistor. After an audio voltage peak has occurred, it is not desirable that the condenser 16 of Figures 1 to 4 shall begin at once to discharge at the maximum rate. The production of a smooth envelope current is favored by delaying the discharge so that it reaches full rate only after the modulation has fallen considerably. Dimmick therefore proposes to control the passage of discharge current through the photocell by varying the illumination of the cathode of the cell by means of a lamp whose current is controlled in a suitable manner. The marginal circuit shown in my Figures 1 to 3 provides a convenient source of voltage for controlling the illumination produced by a lamp such as disclosed in the Dimmick application. Figure 4 shows a modification of my circuits comprising the photocell discharge feature. In nearly all respects, Figure 4 is the same as Figure 3 with the exception that resistance 15 is replaced by photocell 42 which in turn is illuminated by lamp 41. The brightness of lamp 41 is controlled by electron discharge tube 40 whose grid or control voltage is derived from the marginal rectifier. The grid of the tube is so connected that, when there is modulation present and an appreciable rectified voltage produced by rectifiers 23, the negative bias on the grid of electron discharge tube 40 is increased, thereby reducing the lamp current. Thus, discharge of condenser 16 is retarded by low illumination of the photocell so long as there is appreciable modulation affecting the margin circuit voltage. With the margin circuit exactly as in Figure 3, the expedient just described might tend to produce too much of an off and on effect or cause the lamp to be either brightly illuminated or dark. It would normally be advantageous to have the brightness of the lamp 41 progressively decreased by the magnitude of the audio signal rather than to have an off-on effect as already mentioned. This can be readily accomplished without impairing the sharply limiting effect on the circuit on the rectified voltage employed for margin, by adding a resistance 32 through which the rectified current provided by the rectifier 23 must pass before reaching the loading circuit 21-22. The voltage applied to the grid of discharge tube 40 is thus the sum of the limited voltage and a voltage which continues to increase as the modulation rises, namely, the resistance drop across resistance element 32. With this arrangement, photocell 42 is substantially nonconducting, while there is high modulation, and, as the modulation falls, it tends to carry more current, thus permitting sufficiently rapid recovery of the circuit after the cessation of modulation.

Figure 5 shows a modification of my invention in which the margin produced by the positive half waves is added to the ground noise reduction system response as produced in the nor-

mal manner by the negative half waves, in a different manner from that of my previous circuits. In Figure 5, the voltages due to positive and negative peaks are combined in a single full wave rectifier, but the objection to the employment of an ordinary full wave rectifier, namely, that the positive peaks being larger than the negative peaks can cause an unnecessarily large margin, is obviated in my Figure 5 by limiting the magnitude of the positive peaks to a value dependent on the magnitude of the negative peaks. In Figure 5, winding 11, resistor 13, rectifier 14, discharge resistance 15, the filter comprising elements 16, 17, and 18, and the output tube 19 function in the same manner as in Figure 1. Also contributing to the charging of condenser 16 are the positive peaks developed in winding 55 of transformer 10 and applied to condenser 16 through rectifier 23. Were the resistance 31 and loading rectifier 21 omitted in Figure 5, and windings 55 and 11 provided the same number of turns, Figure 5 would operate as an ordinary or standard ground noise reduction circuit except that it employed full wave rectification of the usual type. This, as has been previously explained, is open to the objection of producing too much margin because of the greater height of the positive waves. Provision is therefore made in Fig. 5 for limiting the positive waves. In order to make this limit more easily applied and effective, the audio circuit for rectifying the positive peak is made of high impedance by the inclusion of resistance 31. The magnitude of the positive peaks applied to the rectifier 23 is limited by a second rectifier 21 in series with a source of biasing voltage derived in a manner presently to be explained. The loading system operates in the same manner as that in Fig. 1 and limits the peaks to a magnitude substantially equal to the biasing voltage, which in Fig. 1 was supplied by a battery and, therefore, constant, but in Fig. 5 is dependent on the magnitude of the negative peaks. The bias voltage may be made exactly equal to the voltage developed by the negative peaks across condenser 16, but, for purposes of illustration, I have indicated means for causing the bias voltage to slightly exceed that produced by the negative waves. This permits the positive waves to provide a margin which is useful in preventing clipping. In Fig. 1, the bias voltage which prevents current passing through rectifier 21, unless the applied voltage exceeds the bias voltage, was a simple battery and of very low resistance. It is necessary in order that the loading circuit shall be effective that it operate into a low impedance circuit. This low impedance circuit is provided by the relatively large condenser 52 which discharges when modulation ceases through the correspondingly low resistance 54. If condenser 52 were charged by means of negative peaks of the same magnitude as those which operate through rectifier 14 to charge condenser 16, then the positive peaks would be limited to the same magnitude as the negative peaks. In order to provide a margin, I have included additional turns 50 on the secondary of transformer 10, such that the total audio voltage for providing the bias is that developed in windings 11 and 50 in series. The resistor 57 serves the same purpose with reference to winding 50 as the resistor 13 in reference to winding 11, namely, to give the transformer secondary an impedance characteristic which will permit sudden brief charging current. I have shown a battery

53 which may serve either as an alternative or supplementary means of providing the desired slight excess of voltage across condenser 52 as compared with that across condenser 16. It is essential that the transformer 10 be so designed that it is capable of supplying larger instantaneous currents than are ordinarily required in a ground noise reduction system, for the reason that not only must condenser 16 be quickly charged when a negative peak occurs but the much larger condenser 52 must also be charged to the same or perhaps to a higher value. From the foregoing, it will be noted that the voltage across condenser 52 follows closely that across condenser 16 but may be made to have either a slight fixed margin of excess voltage resulting from the use of battery 53 or a small percentage margin resulting from the inclusion of the excess turns 50 in the secondary winding of transformer 10. Since the voltage which can be contributed through rectifier 23 operating it on the positive peaks of the audio waves is limited to the voltage across condenser 52, the positive waves can never result in an increase in total response above that desired, in view of the height of the negative peaks, but a definite and controllable margin can be obtained. The advantage of the circuit of Fig. 5 as compared with the circuits of Figs. 1 to 4 is that the inclusion of positive peaks of magnitude substantially equal to the negative peaks in the system for charging condenser 16 results in the latter normally receiving two charges per cycle of audio frequency voltage, and this results in less fluctuation in the voltage across condenser 18. The fluctuations due to the periodic charging of condenser 16 and its partial discharge in between moments of charging, although filtered by elements 17 and 18, are sometimes a cause of audible disturbances introduced into the sound record by the ground noise reduction system, and the danger of such noises is decreased by charging condenser 16 twice during each audio cycle.

- I claim as my invention:
- 45 1. A ground noise reduction system comprising a half wave rectifier for providing an envelope current, a second rectifier arranged to rectify waves of opposite polarity to those which said first rectifier rectifies, means for limiting the rectified voltage of the second rectifier, and means for adding the voltages derived from said rectifiers.
  - 50 2. Apparatus as defined in claim 1, wherein the second rectifier is a full wave rectifier.
  - 55 3. Apparatus as defined in claim 1 including means for causing the limits imposed by said limiting means to be increased during periods of increasing sound intensity.
  - 60 4. Apparatus as defined in claim 1 including means responsive to increases or decreases in wave amplitude for altering the limiting effect of said limiting means.
  - 65 5. A ground noise reduction system comprising a rectifier for providing a rectified voltage substantially proportional to peak voltages of specified polarity of waves to be recorded, means including a second rectifier for providing a marginal voltage above the voltage of said first rectifier, and nonlinear limiting means whereby said margin is restricted to a value substantially less than the maximum voltage derived from said first rectifier.
  - 70 6. A ground noise reduction system including means for rectifying electrical waves of one polarity, means for rectifying electrical waves of
  - 75

the opposite polarity, means for adding the voltages of said rectified waves, and means for limiting one of said voltages to a predetermined value.

7. A ground noise reduction system including means for rectifying electrical waves of one polarity, means for rectifying electrical waves of the opposite polarity, means for adding the voltages of said rectified waves, and means for limiting one of said voltages to a value not exceeding the other voltage by more than a limited amount.

8. A ground noise reduction system including means for rectifying electrical waves of one polarity, means for rectifying electrical waves of the opposite polarity, means for adding the voltages of said rectified currents, and means for limiting one of said voltages to a value not exceeding the other voltage by more than a predetermined amount.

9. A ground noise reduction system including means for rectifying electrical waves of one polarity, means for rectifying electrical waves of the opposite polarity, means for adding the voltages of said rectified currents, and means for limiting one of said voltages to a value not exceeding the other voltage by more than a predetermined percentage.

10. A ground noise reduction system including means for rectifying electrical waves of one polarity, means for rectifying electrical waves of the opposite polarity, means for adding the voltages of said rectified currents, and means for limiting one of said voltages to a value not exceeding the other voltage by more than a predetermined fixed amount.

EDWARD W. KELLOGG.
